UNITED STATES PATENT OFFICE.

FRANK W. WESTER, OF REYNOLDS, NORTH DAKOTA.

SELF-MEASURING STOCK FEEDER.

1,406,125.

Specification of Letters Patent. Patented Feb. 7, 1922.

Application filed April 10, 1920. Serial No. 372,826.

To all whom it may concern:

Be it known that I, FRANK W. WESTER, a citizen of the United States, residing at Reynolds, in the county of Grand Forks and 5 State of North Dakota, have invented certain new and useful Improvements in Self-Measuring Stock Feeders; and I do hereby declare the following to be a full, clear, and exact description of the invention, such as 10 will enable others skilled in the art to which it appertains to make and use the same.

This invention has relation to certain new and useful improvements in self measuring stock feeder and has for its primary object, 15 the provision of a self measuring stock feeder of simple and efficient construction and operation and comparatively inexpensive.

Another object of the invention resides 20 in the provision of a self measuring stock feeder, the valves of which determine the amount of stock to be fed or delivered from the supply receptacle, the valves being arranged in such a manner that one of the 25 valves may be adjusted with respect to the other to vary the quantity of stock fed or delivered from the supply receptacle.

The invention has for a further object, 30 the provision of a self measuring stock feeder of the above stated character in which the valves will be mounted in a novel manner and resiliently retained in normal position so that after the operation to release the predetermined quantity of stock, the 35 valves will be returned to normal position to permit the feeding or measuring tube to be again filled from the supply receptacle or tank above the same and communicating therewith.

40 With the foregoing and other objects in view, as will be hereinafter more specifically set forth, pointed out in the appended claims and shown in the accompanying drawings forming a part of this application, the invention consists in the novel construction, combination and arrangement of co-operating elements as disclosed in this application.

In the drawings forming a part of the 50 application:—

Figure 1 is a side elevation of the structure embodied in this invention.

Figure 2 is an elevation at right angles to Figure 1.

Figure 3 is a vertical section on the plane

of line 3—3 of Figure 2, looking in the direction indicated by the arrow.

Figure 4 is a perspective view of the primary valve and operating lever, removed.

Figure 5 is a similar view of the intermediate lever.

Figure 6 is a similar view of the secondary lever and valve, removed.

Referring more in detail to the drawings in which similar reference characters designate corresponding parts throughout the several views, 1 indicates a suitable feed supply receptacle from which depends the feed tube 2, the lower portion of which is increased in width by having one side open 70 and the parallel side supporting members or plates 3 extended from the opposite edges of the open side of the lowermost tube 2, as clearly shown in the drawings. A pair of pivot pins 4 and 5 are mounted in the lever supporting plates 3, outwardly of the lower portion of the tube 2, as clearly shown in Figures 1 to 4 inclusive of the drawings.

The main or primary valve and operating lever 6 is mounted upon the upper and innermost pivot pin 4 and includes an upwardly and outwardly extended portion 7 and a lower outwardly curved portion 8. This member also includes a horizontally di- 80 rected valve 9, above the pivot point of the member and which extends transversely through the tube 2 at the upper end of the plates 3, this valve plate 3 projecting through a slot 10 in the rear wall of the tube 2 and having downwardly directed fingers 11 to limit inward movement of the valve plate 9 through the tube 2 in one direction. The valve plate 9 has a transverse slot 12 which registers with the passage of

the tube 2 when the primary valve and operating lever 6 is in normal position. This member 6 is resiliently retained in normal position by the spring 13 which has one end secured to the upper portion 7 of the member 6 while its opposite end is secured to the 100 opposite side wall of the tube 2, as clearly shown in the drawings.

An intermediate lever 14 is employed and has depending leg portions 15 which are turned with respect to the main portion 105 of the lever 14 and pivotally mounted on the pivot pin 4. The main or upper portion of this intermediate lever 14 is resiliently retained in spaced relation with respect to the upwardly directed portion 7 of the mem- 110

ber 6 and outwardly thereof by means of the second coil spring or expansion spring 16 having one end secured to the intermediate lever 14 and opposite end to the member 6, 5 as clearly shown in Figure 3 of the drawings.

The secondary valve 17 has a curved lower end 18 which is normally in contact with the rear wall of the tube 2, adjacent the lower 10 ends of the plates 3. This valve 17 has a number of opposed teeth 19 along its opposite edges and directed outwardly to form notches 20 to receive the pivot pin 5 so that the secondary valve may be readily 15 adjusted with respect to the primary valve and operating lever 6 so as to vary the amount of feed to be delivered each time the valves are operated. The parts are so arranged that the lever 14 engages the inner 20 face of the secondary valve 17 adjacent the upper end thereof, as shown in Figure 3, while the outwardly curved lower end 8 of the member 6 contacts with the inner face of the secondary valve 17 at a 25 point below the pivot pin 5. It will therefore be seen that when the upper end 7 of the member 6 is pressed inwardly toward the tube 2, to close the tube 2 by the solid portion of the valve plate 9 being 30 forced across the tube at the upper edge of the plate 3 or the measuring compartment as it may be termed, the secondary valve stem will be forced outwardly, thereby forcing the lower curved end of this valve away 35 from the wall of the tube 2 to permit the feed between the valves 9 and 17 to pass out of the tube 2. As soon as the primary valve and operating lever 6 are released, however, the springs 13 and 16 will act to return the 40 valves and all movable parts to normal position, thereby again closing the tube 2 at its lower extremity by the curved end 18 of the secondary valve 17 and opening the tube 2 at the upper ends of the plate 3 or 45 feed measuring pocket by again bringing the transverse slot 12 of the valve 9 into registration with the tube 2.

It is believed that the complete construc-

tion and operation of this invention may be understood by reference to the drawings 50 without further detail description. It is evident, however, that minor changes in the details of construction and arrangement of parts may be resorted to within the scope of the appended claims without departing 55 from the spirit of the invention.

What is claimed is:

1. A device of the class described having a dispensing portion, a lever to normally close the portion, an operating lever one 60 end of which is in contact with said first named lever, means to urge the levers into such contact, means to normally urge the second lever at the other end away from the dispensing portion, and a cut-off valve for 65 such portion operable by the second lever.

2. A device of the class described having a dispensing portion, a lever to normally close the portion, an operating lever one end of which is in contact with said first 70 named lever, means to urge the levers into such contact, consisting of a plate pivoted to one of the levers and bearing against the other lever, and an expansive spring bearing against the plate and the opposite lever. 75

3. A device of the class described having a dispensing portion with side walls and an end wall, a lever intermediate the side walls with its end normally in contact with the end wall, a second lever intermediate the 80 side walls serving as an end wall thereof, said second lever at one end contacting with the first lever and at its other end functioning as a handle, a plate pivoted to one of the levers and bearing against the other 85 lever, means to urge the levers and plate into operative relation, and a cut-off valve for the dispensing portion movable with the second lever.

In testimony whereof I affix my signature 90 in presence of two witnesses.

FRANK W. WESTER.
